W. C. DILLON

SHEARING DEVICE FOR AUXILIARY LOCKS

Filed April 17, 1922

Inventor

William C. Dillon
By
Bair & Freeman

UNITED STATES PATENT OFFICE.

WILLIAM C. DILLON, OF FORT DODGE, IOWA, ASSIGNOR TO LE ROY DILLON, OF FORT DODGE, IOWA.

SHEARING DEVICE FOR AUXILIARY LOCKS.

Application filed April 17, 1922. Serial No. 553,592.

To all whom it may concern:

Be it known that I, WILLIAM C. DILLON, a citizen of the United States, and resident of Fort Dodge, in the county of Webster and State of Iowa, have invented a certain new and useful Shearing Device for Auxiliary Locks, of which the following is a specification.

An object of my invention is to provide a shearing device for releasing the flexible member used in connection with auxiliary locks for vault doors.

A further object is to provide such a shearing device wherein the flexible element is passed between a bar which extends across the face of the combination lock of the vault door, and the upper edge of a slot or the like in a post which is received in an opening in the bar.

20 A further object is to provide such a shearing device in which the parts are so arranged that a slight movement of the combination lock will cause the bar to move relative to the post, and to cut the flexible element in order to release it.

An additional object is to provide an adjustable mounting for securing one end of the bar and means for adjusting the height of the post.

30 Reference is here made to my co-pending application, Serial Number 553,593, filed April 17, 1922.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Figure 1 shows a sectional view through a portion of a vault illustrating the inside of the door in locked position, with an auxiliary locking device and the shearing device installed thereon.

Figure 2 is an enlarged view of my shearing device installed over the combination lock of the vault door.

Figure 3 is a sectional view through the vault door, the shearing device appearing in elevation; and

Figure 4 is a detailed sectional view illustrating the coaction of the shearing bar with the post, taken on the line 4-4 of Figure 2.

In the accompanying drawings, I have used the reference numeral 10 to indicate generally, a vault door having an inwardly extending flange or strip 11 spaced from its edges. Locking bolts 12 are slidably mounted in the flange 11 and adapted to engage the inner edge of the door casing 13.

The bolts 12 are connected by a bar 14, which is operated back and forth, for sliding the bolts, by the actuating fingers 15 and the handle 16, (see Figure 3).

The type of auxiliary lock shown in connection with my present invention comprises a bolt 17 set into the flange 11 and extending laterally behind the bar 14. A locking block 18 is mounted on the bolt 17 for rotation thereon, and is normally held in such a position that the bar 14 may slide by it.

A flexible element 19 anchored at one end, is used to hold the block 18 in this position against the action of a spring 20 which tends to rotate the block 18 on the bolt 17. When the flexible element 19 is released, the block 18 is rotated, and is of such shape that a portion of it will obstruct the path of the bar 14 and prevent the sliding of the bolts 12 for opening the door.

Below the combination lock 19, a stud bolt 20 is mounted in the vault door. A post 21 is threaded on the stud 20 for adjustment as to height.

Above the combination lock is a stud bolt 22 which is threaded into the door 10. A shearing bar 23 is mounted on the stud 22 and secured in place by nuts 24 and 25 above and below the bar respectively. The nuts 24 and 25 are so adjusted that a little motion of the bar 23, relative to the bolt 22 will be permitted.

The bar 23 extends across the face of the combination lock 19 and at its lower end has a circular opening 26 which is of slightly larger diameter than the post 21. The bar 23 is received over the post 21.

In the post 21 is a peripheral slot or groove 27, which is of sufficient depth and width to receive snugly the flexible member 19. A loop 28 in the end of the member 19 is provided, which rests in the slot 27.

The shearing bar 23 is so adjusted that it practically touches the face of the combination lock and is about flush with the edge of the slot 27, behind the loop 28. In order to adjust the bar 23 to this position,

the nuts 24 and 25 may be adjusted, and the post 21 rotated on the stud 20.

In order to prevent injury to the loop 28 while so adjusting the bar, an annular slot 29 is provided in the post 21, spaced from the slot 27 in such a position as to receive a pin 30 which is fixed in the bar 23 and extends from edge to edge thereof.

It will be seen that the pin 30 tends to prevent any movement of the bar 23 relative to the post 21. The pin 30 is of soft material, however, so as to be easily sheared when the pressure is brought against the bar.

15 The flexible member 19 is extended from the post 21 around a pulley 31 and thence to the auxiliary locking block 18. It will be seen that the post 21 acts as an anchor for holding the element 19 under tension.

20 In locks of this type, the flexible element is generally passed across the face of the combination lock, and the breaking of the flexible element by the forcing in of the combination lock, is relied upon to operate the lock. I have found, however, that it is possible for two men to open the door without operating the auxiliary lock. The way in which this is accomplished is as follows:

25 One man procures a length of pipe suitable to be slipped over the end of the handle 16.

30 Using this as a lever, he exerts a tremendous pressure against the actuating fingers 15. While he is applying this pressure, the combination lock is blown off or punched in. It has been found that the release of the fingers 15 is accomplished enough ahead of the severing of the flexible element to allow the bar 14 to be shot across the path of the auxiliary lock, thus fouling its action.

35 It has also been found that, in some types of combination locks, by forcing the lock inwardly, less than one-eighth of an inch, it may be displaced laterally a sufficient amount to release the fingers 15.

40 In the practical operation of my shearing device, the movement of the combination lock a slight distance will cause the bar 23 to be forced outwardly, the stud 22 acting as a pivot. The pin 30 will first be cut, and then the loop 28, where it crosses the edge of the hole 26, will also be sheared; releasing the auxiliary lock.

45 The advantages of this method of releasing the flexible element lies in the fact that only a slight displacement of the combination lock is necessary in order to cut the flexible element. The operation of the auxiliary lock must therefore precede the releasing of the bar 14.

50 It will be understood that changes may be made in the construction of my device, without departing from the real purpose

and spirit of my invention. For instance, the bar 23 might be made fixed and the post 21 made movable by placing one end of it against the face of the combination lock and allowing the other end to pass through as an opening in the bar 23. It is my intention, to cover by my claims all modified forms of structure which may reasonably be included within their scope.

55 I claim as my invention:

1. In combination with an auxiliary lock for a vault door having a combination lock thereon, said auxiliary lock including a flexible element for holding said lock in inoperative position, a shearing device for releasing said flexible element, said shearing device including a post below the combination lock, a stud bolt above the combination lock, a bar having an opening therein adapted to receive the post, said bar being extended across the face of the combination lock and mounted on the stud bolt at its other end, and said post having a slot flush with the outer face of the bar, the flexible element being attached to the post by means of a loop resting in said slot.

2. In combination with an auxiliary lock for a vault door having a combination lock thereon, said auxiliary lock including a flexible element for holding said lock in inoperative position, a shearing device for releasing said flexible element, said shearing device including a post adjacent to the combination lock, a bar suitably mounted on the vault door and crossing the face of the combination lock, said bar having an opening at one end adapted to receive the post, and said post having a slot flush with the outer face of the bar, the flexible member being passed through said slot in such a manner that the movement of the bar relative to the post will cut the flexible element.

3. In combination with an auxiliary lock for a vault door having a combination lock thereon, said auxiliary lock including a flexible element for holding said lock in inoperative position, a shearing device for releasing said flexible element, said shearing device including a post adjacent to the combination lock, a bar suitably mounted on the vault door and crossing the face of the combination lock, said bar having an opening at one end adapted to receive the post, and said post having a slot flush with the outer face of the bar, the flexible member being passed through said slot in such a manner that the movement of the bar relative to the post will cut the flexible element and the post being adjustable toward the vault door.

4. In combination with an auxiliary lock for a vault door having a combination lock thereon, said auxiliary lock including a flexible element for holding said lock in inoperative position, a shearing device for re-

leasing said flexible element, said shearing device including a post having a groove therein, a bar extended across the face of the combination lock, said bar being fixed at one 5 end, and having an opening in the other end designed to coat with said post, the flexible element being extended across the face of the bar into said groove.

5. In combination with an auxiliary lock 10 for a vault door having a combination lock thereon, said auxiliary lock including a flexible element for holding said lock in inoperative position, a shearing device for releasing said flexible element, said shearing device including a post below the combination lock, a stud bolt above the combination lock, a bar having an opening therein adapted to receive the post, said bar being extended across the face of the combination lock and 15 mounted on the stud bolt at its other end, said post having a slot flush with the outer 20

face of the bar, the flexible element being passed across the face of the bar and through said slot, and the bar being adjustable toward the face of the combination lock by 25 means of nuts above and below the bar on the stud bolt.

6. In combination with an auxiliary lock 30 for a vault door having a combination lock thereon, said auxiliary lock including a flexible element for holding said lock in inoperative position, a shearing device positioned adjacent to the combination lock and operable by the abnormal movement thereof for severing said flexible element, said shearing 35 device including a post member to which the flexible element is secured and a pivoted bar for shearing the flexible element as and for the purposes stated.

Des Moines, Iowa, April 6, 1922.

WILLIAM C. DILLON.
